Primary Examiner — Barbara Fox*Assistant Examiner* — Alyse Joseph(74) *Attorney, Agent, or Firm* — Banner & Witcoff, Ltd.(57) **CLAIM**

The ornamental design for a display screen with animated graphical user interface, as shown and described.

DESCRIPTION

FIG. 1 is the first image in a sequence for a display screen with animated graphical user interface showing my new design;

FIG. 2 is the second image thereof;

FIG. 3 is the third image thereof;

FIG. 4 is the fourth image thereof;

FIG. 5 is the fifth image thereof; and,

FIG. 6 is the sixth image thereof.

The appearance of the animated graphical user interface sequentially transitions between the images shown in FIGS. 1-6. The process or period in which one image transitions to another forms no part of the claimed design. The dot-dash lines in the figure illustrate the bounds of the claim. The dash-dash broken line showing of a display device illustrates environment. The remaining broken lines illustrate portions of the display screen with animated graphical user interface. The broken lines form no part of the claimed design.
